Patented July 4, 1922.

UNITED STATES PATENT OFFICE.

WILLIAM ERASTUS WILLIAMS, OF CHICAGO, ILLINOIS.

QUICK-DETACHABLE DUST CAP FOR PNEUMATIC TIRES.

1,421,642.

Specification of Letters Patent.

Patented July 4, 1922.

Application filed July 6, 1920. Serial No. 394,153.

To all whom it may concern:

Be it known that I, WILLIAM ERASTUS WILLIAMS, a citizen of the United States, a resident of Chicago, in the county of Cook and State of Illinois, have invented a new and useful Improvement in Quick-Detachable Dust Caps for Pneumatic Tires, of which the following is a specification.

My invention relates to dust caps which 10 enclose and protect valve stems.

The object of my invention is to provide a very cheaply constructed, quick detachable cap that may be applied to and removed from the valve stem in the most expeditious 15 manner and at the same time be adjusted along the valve stem and be practically secure against accidental displacement.

Reference will be had to the accompanying drawings in which Figure 1 is a sectional elevation of a part of a rim of a wheel with my 20 valve cap in place.

Figure 2 is an enlarged central sectional view similar to that of Figure 1.

Figure 3 is a detail sectional view of the 25 valve cap itself on the same scale as that of Figure 2.

Figure 4 is a transverse sectional view when the cap is secured in place.

Figure 5 is a view similar to that of Figure 30 4 showing the position of the parts when my cap is being pushed on to the valve stem.

In the drawing 1 indicates the felloe and rim of a wheel which may be of any desired type and no details of this are given. 2 indicates a section through the rubber tube to which the valve stem 3 is secured in any suitable way. On the end of this stem is the ordinary cap 4 generally used with valve stems. The standard ordinary valve stem 40 has two flattened surfaces indicated by 5 and these surfaces are on the sides in Figure 2.

The valve stem 3 is threaded its entire length but as above stated it is flattened so that the threads are wanting on the sides 45 and appear only on the surfaces indicated by 6 in Figures 4 and 5.

My valve cap is indicated by 7 and is shaped in cross section as shown in Figures 4 and 5 wherein there are swells or recessed 50 pockets 8 on two sides and in these recesses there is mounted peculiarly shaped spring 9 which is secured into the head of the valve cap by a rivet 10 or by other suitable means.

The spring 9 is provided with contact surfaces 11 adapted to fit the sides 5 of the valve stem but there is sufficient elasticity in the body of the spring to permit the valve stem

to be turned 90 degrees from the position of Figure 4 to that of the position of Figure 5 wherein the spring contact surfaces 11 press 60 on the thread surfaces 6 of the stem. In this position the valve cap 7 may be pushed on or removed from the valve stem by slight force.

In the lower end of my cap I provide 65 threads 12 mutilated so as to provide only narrow bearing thread portions as indicated in Figures 4 and 5. In Figure 4 my threads 12 are in engagement with the threads 6 of the valve stem but in Figure 5 the threads 70 12 are opposite the flat surfaces 5 of the valve stem itself.

In Figure 4 the bearing surfaces 11 embrace the flat surfaces 5 of the stem and act as a nut lock to prevent the turning of the 75 cap on the valve stem and the threads 12 are in engagement with the threads 6 and thus the cap is held securely in place.

When it is desired to remove the cap 7 it is 80 revolved 90 degrees, disengaging the threads 12 and bringing the contact surfaces 11 on to the thread 6 and then the valve cap may be pulled off. On replacing the dust cap 7 it is positioned on the end of the valve stem as shown in Figure 5 and pushed as far as desired, usually against a nut 13 screwed 85 against the felloe.

What I claim is:—

1. A tubular dust cap having a short section provided with internal mutilated 90 threads and with a stem-pressing spring fixed to the cap, lying in a non-threaded portion thereof and normally projecting within the circle of the threaded portion of a valve stem upon which it may be placed. 95

2. The combination with a valve stem member having external threads cut away along a longitudinal line, of a stem-enclosing dust cap member having mutilated threads adapted to engage and disengage the stem 100 threads during relative rotation, and spring devices between said members constantly pressing them at various points in their length and resisting while permitting their relative rotation.

3. In a device of the class described, a tubular dust cap having a U shaped spring secured within the cap and adapted to press on two sides of the valve stem over which the cap is placed. 110

4. In a device of the class described, a dust cap composed of a tubular member adapted to be applied over the spindle of an air valve and said tubular member having threaded

portions on the inside and opposite each other and for only short sections around the circumference; in combination with recesses on the inside of the cap located at 90 degrees 5 from the said thread portions of the cap and with spring contact devices located within the recessed portions.

Signed at Chicago, in the county of Cook and State of Illinois, this twenty-ninth day of June, 1920.

WILLIAM ERASTUS WILLIAMS.
